US00D800090S

(12) **United States Design Patent** (10) **Patent No.:** **US D800,090 S**
(45) **Date of Patent:** **** Oct. 17, 2017**

(54) **WIRELESS HEADSET**

- (71) Applicant: **LG Electronics Inc.**, Seoul (KR)
- (72) Inventors: **Yooshin Ahn**, Seoul (KR); **Seungbeom Park**, Seoul (KR)
- (73) Assignee: **LG ELECTRONICS INC.**, Seoul (KR)
- (**) Term: **15 Years**
- (21) Appl. No.: **29/565,430**
- (22) Filed: **May 20, 2016**

Related U.S. Application Data

- (63) Continuation of application No. 29/535,584, filed on Aug. 7, 2015, now Pat. No. Des. 774,017.

(30) **Foreign Application Priority Data**

- Feb. 9, 2015 (KR) 30-2015-0006877
- (51) **LOC (10) Cl.** **14-01**
- (52) **U.S. Cl.**
USPC **D14/205**
- (58) **Field of Classification Search**

(57) **CLAIM**

The ornamental design for wireless headset, as shown and described.

DESCRIPTION

FIG. 1 is a perspective view of a wireless headset showing our new design;

FIG. 2 is a front view thereof;

FIG. 3 is a rear view thereof;

FIG. 4 is a left side view thereof where the right view is a mirror image;

FIG. 5 is a top plan view thereof;

FIG. 6 is a bottom plan view thereof;

FIG. 7 is a reference view thereof showing the state that the earphone part and the main body can be detached; and, FIG. 8 is a reference view thereof showing an example of the usage of the subject design.

The broken lines depict portions of the wireless headset for the purposes of illustration that form no part of the claimed design.

1 Claim, 7 Drawing Sheets
